UNITED STATES PATENT OFFICE.

CHARLES R. TWITCHELL, OF DAYTON HEIGHTS, CALIFORNIA, ASSIGNOR TO BROWN-WINSTANLEY MANUFACTURING COMPANY, OF LOS ANGELES, CALIFORNIA, A CORPORATION OF CALIFORNIA.

ROTARY EXPLOSIVE-ENGINE.

SPECIFICATION forming part of Letters Patent No. 783,336, dated February 21, 1905.

Application filed July 31, 1903. Serial No. 167,748.

To all whom it may concern:

Be it known that I, CHARLES R. TWITCHELL, of Dayton Heights, in the county of Los Angeles and State of California, have invented 5 certain new and useful Improvements in Rotary Explosive-Engines; and I do hereby declare the following to be a full, clear, and exact description of the invention, such as will enable others skilled in the art to which it applies to make and use the same.

The object of this invention is to provide simple and highly-efficient means for actuating the controlling-valves of the several cylinders of a rotary explosive-engine, such 15 means being adjustable while the engine is in operation, so as to control the speed thereof.

The invention will be hereinafter fully set forth, and particularly pointed out in the claims.

20 In the accompanying drawings, Figure 1 is a view in perspective. Fig. 2 is a similar view with parts broken away, but viewed oppositely to Fig. 1. Fig. 3 shows in detail the connections between the piston-rods and the 25 stationary crank. Fig. 4 is a fragmentary view in perspective, showing the means for introducing the gases.

Referring to the drawings, 1 designates a supporting-base, and 2 parallel uprights, one 30 forming bearings for a stationary crank-shaft 3, preferably keyed to prevent rotation. The crank 4 on the inner end of the shaft 3 has a pin 5 extending laterally therefrom and designed to form the bearing for the inner ends 35 of the piston-rods 6, whose pistons are movable longitudinally of cylinders 7, fixedly mounted between two parallel disks 8 and 9, the former being carried by the crank-shaft and the latter by a second shaft in axial line 40 with the crank-shaft and having its bearings in the other upright 2. The piston-rods at their inner ends have laterally - extended curved flanges 10, one of which enters an annular channel or groove 12 in the face of 45 crank 4 concentric with the crank-pin 5, while

the other flanges of the several rods are engaged by a cap or collar 13, secured to the end of the crank-pin by a bolt 14. In this way the inner ends of the several piston-rods are secured to the crank-shaft, and while they 50 are permitted to freely revolve around pin 5 friction between the parts is greatly reduced, and in addition thereto they may be readily removed upon loosening bolt 14 and withdrawing the cap or collar 13.

Concentric with the horizontal portion of the crank-shaft 3 and adjacent to the crank 4 thereof is a pinion 16, from which extends a right-angular arm 17, the free end whereof is coincident with an opening extending longitudinally through the crank-shaft. Within this opening is located a rod 18, having a handle or crank on its outer end, while its inner end is made fast to the free end of arm 17, so that by turning rod 18 pinion 16 may be made 65 to revolve. With this pinion mesh a series of larger pinions or gear-wheels 19, having their bearings on the inner face of disk 8. Each of these gear-wheels carries a pin 20 for engaging a lever 21, fulcrumed on disk 8, one lever 70 being provided for each cylinder. These several levers at their outer ends engage valve-stems 22, mounted in the exhaust-outlets of such cylinders. It follows from what has been said that the valve-actuating lever 21 of 75 each cylinder is operated once upon each revolution of its coaxing gear-wheel 19. To effect a change in the time or the position in which these valve-operating levers will be actuated to unseat the exhaust-valves, it is only 80 necessary to axially turn rod 18, which through pinion 16 will rotate gear-wheels 19 independently of their rotation occasioned by their revolution around such pinion in the operation of the engine—that is to say, when it is desired to increase the speed of the engine the 85 several gear-wheels are so positioned through the instrumentality of rod 18 and pinion 16 that the levers 21 will unseat the exhaust-valves sooner after the explosion than when 90

running at a slower speed, the actuation of the levers being then postponed until the full force of the charge has been spent.

- The exhaust from each cylinder—that is, 5 the exhaust controlled by the lever-actuated valves—passes through a pipe or conduit 23, which opens into disk 9. This disk is formed with two parallel spaced-apart walls, the intermediate chamber thus formed constituting 10 a muffler, from which the burned gases may escape through exhaust-ports 24, formed in the outer wall thereof. The several cylinders may also be provided with auxiliary exhaust-ports 25, opening directly into the muffler, as 15 clearly shown in Fig. 2. In this way I avoid exhausting directly into the atmosphere, and the advantage of exhausting into a muffler rotating with the several cylinders will be at once appreciated.
- 20 The charging-gases are introduced through an inlet-pipe 26, (shown in Figs. 1 and 4,) which is carried into one of the uprights 2 and opens at its inner end into an annular supply-chamber 27, through which the shaft 25 3 is centrally extended. The hub 28 of disk 8, encircling shaft 3, extends into chamber 27 to near the outer wall thereof and is formed with longitudinal ports 29, through which the charge passes to pipes or conduits 30 and 30 through them into the explosion-chambers 31 of the several cylinders. There the charge is exploded by any suitable means, although I prefer to employ the jump-spark, which may be communicated through wires 32, secured 35 to contact-posts 33, which posts engage an electrically-charged pin 34 of a lever 35, carrying a second electrically-charged pin 36, designed to be engaged by a pin 37 of a pinion 38, which meshes with a pinion 39, mounted 40 on hub 28. The primary connection is with pin 36, while the secondary connection is had with pin 34, the complementary wires of each connection being secured to the base at any point.
- 45 The operation is as follows: The actuating medium being introduced through inlet-pipe 26 is, as is well known, induced into the explosion-chambers by the downward or inward movements of the pistons, the gases freely 50 traveling from the annular chamber 27 through ports 29 and conduits 30 into the explosion-chambers of the several cylinders. After the explosion occurs in a cylinder (and it is by the several explosions that the cylinders and 55 the two disks carried thereby are caused to rotate around the stationary crank-shaft) the burned gases are permitted to escape into the muffler upon the several levers 21 being actuated by pins 20 of gear-wheels 19 to unseat 60 the exhaust-controlling valves. To stop the engine or to regulate the speed, it is only necessary to turn rod 18 so that through pinion 16 the lever-actuating gear-wheels will be

rotated in their bearings independently of their revolution with their carrying-disk. 65 The engine is of the four-cycle type, the charge of each alternate cylinder being exploded as they revolve around the crank-shaft. This is due to the fact that the gear-pinion 39 has half as many more teeth as the gear-pinion 38. 70

While I have shown in the drawings a preferred form of construction for carrying out my invention, yet it is to be understood that I do not confine myself to any special form of mechanism for accomplishing the object of 75 my invention.

I claim as my invention—

1. In a rotary explosive-engine, in combination, a series of cylinders having exhaust-controlling valves, means for operating the 80 valves, means independent of the valve-operating means for periodically actuating such means during the revolutions of the cylinders, and means for regulating or adjusting, while the engine is in operation, the time of 85 actuation of such periodically-actuating means to control the speed of the engine.

2. In a rotary explosive-engine, in combination, a series of cylinders having exhaust-controlling valves, levers for actuating the 90 same, means independent of said levers for operating them periodically during the revolutions of the cylinders, and means for regulating or adjusting, while the engine is in operation, the time of actuation of such levers 95 by said latter means.

3. In a rotary explosive-engine, in combination, a series of rotary cylinders, means rotating therewith for effecting the exhaust therefrom, a series of gear-wheels independent of but designed to actuate such means, an independently-mounted pinion with which said gear-wheels engage, and means for turning such pinion to adjust the positions of said gear-wheels relatively to said exhaust-effecting means for controlling the speed of the engine. 100

4. In a rotary explosive-engine, in combination, a series of rotary cylinders, means rotating therewith for effecting the exhaust therefrom, comprising a series of levers for unseating the exhaust-valves, gear-wheels mounted independently of said levers and having pins for engaging the latter to allow the several cylinders to exhaust, an independently-mounted pinion with which said gear-wheels engage, and means for turning such pinion to adjust the positions of said gear-wheels and their pins relatively to said levers, to control the speed of the engine. 110

5. The combination with the hollow shaft, of the series of cylinders having their piston-rods engaging such shaft, each cylinder having means for controlling the exhaust, comprising a lever and a coacting gear-wheel 115 mounted independently of the lever, a pinion 120

concentric with said shaft by which the several gear-wheels are rotated as they revolve there-around, and a crank-rod extended through said shaft and connected to said pinion for turning the latter to effect the adjustment of said gear-wheels relative to their respective levers, as set forth.

In testimony whereof I have signed this specification in the presence of two subscr-
ing witnesses.

CHARLES R. TWITCHELL.
